DESK CALENDAR

John F. Bannon, Providence, R. I., assignor to
 Defiance Sales Corporation, New York, N. Y.,
 a corporation of New York

Application June 24, 1941, Serial No. 399,464

2 Claims. (Cl. 40—120)

My invention relates to desk calendars, that is, to calendars comprising a horizontal or slightly inclined base on which a calendar pad is supported, and it relates more particularly to means for mounting an indicating device, such as a thermometer, hygrometer, timepiece, or other such device, in suitable position on the calendar.

Desk calendars are of a variety of types and constructions. One type to which the present invention may be applied to advantage comprises a base slightly inclined from the horizontal and of a width somewhat greater than twice the width of the calendar pad itself so that the pad may be mounted when opened in the manner of a book, with one part to the right of a median line and the other part to the left thereof, there being a bale shaped or two legged post, or pair of such posts, extending upwardly from said base and spanning said median line and threaded through the calendar pad so the calendar leaves may be turned from one side of the line to the other.

In the use of a calendar of the above type, the pad is first placed on one side, generally the right side, of the median line and then as the days pass the leaves of the calendar pad are transferred to the opposite side, with the result that at the beginning of the year the full or complete pad is at the right of the median line and towards the end of the year it is at the left.

In my present invention I provide a support for a thermometer, humidity gauge, or similar device or combination of devices, that may be engaged between the calendar pad and the base on which it is supported and squarely held in position thereon and which may be shifted relative to the median line of the base from the left to the right side thereof, or vice versa, so that it may be placed on the side opposite the full or complete pad itself and, therefore, plainly visible. For this purpose the instrument support comprises a plate to rest on the base of the calendar and on which the calendar sheets, or calendar pad, may bear, and this plate is provided with slots through which the upright posts pass and which are of sufficient length to permit the plate to be slid from one side to the other of the base. The plate is extended upwardly from the rear edge of the base to form an upright in which may be mounted the instruments or indicators, which may be of the dial or other type.

My invention may also be applied to other types of desk calendars; for example, one in which the calendar pad is clamped near its upper edge by a plate which is in turn secured to a pair of spaced posts extending upwardly from the base through

aligned openings in the calendar pad. For this purpose the plate of the instrument support may be provided with additional notches or recesses through which the posts are threaded. The plate of the indicator or instrument support will thus be clamped between the base and the bottom of the calendar pad. A single instrument support may thus serve for a large variety of types and sizes of calendar pads.

10 The various features of the invention are illustrated, by way of example, in the accompanying drawings in which Fig. 1 is a front view of a double or book type of desk pad with the calendar pad on the right half of the base and the instrument support on the left half in balanced relation. Fig. 2 is a view similar to that of Fig. 1 with the instrument and desk pad in positions reverse to those of Fig. 1. Fig. 3 is a plan view of the calendar and instrument support with the pad in the position shown in Fig. 1. Fig. 4 is a vertical longitudinal section through the median or central line of the calendar. Fig. 5 is a vertical view on the line 5—5 of Fig. 4. Fig. 6 is a plan view of another type of calendar with the instrument support mounted therein. Fig. 7 is a detail perspective view of a part of the base and instrument support with the calendar pad removed, and Fig. 8 is a vertical section of a part of the base and instrument support taken on line 8—8 of Fig. 6, showing the manner of securing the pad and support in position on the base.

In the embodiment of the invention shown in Figs. 1 to 5 inclusive, the calendar comprises a base 10 which may be supported on feet 11, with a 35 slightly inclined upper or top surface 12 on which a calendar pad 13 is supported. The base 10 may be of any suitable material as, for example, stamped from sheet metal, or may be molded from plastics, or may be a combination of 40 metal and plastic parts. In the present invention, however, the base is illustrated, in the accompanying drawings, as made of stamped metal.

The width of the base 10 is somewhat greater than twice the width of the calendar pad 13 so 45 that all, or part of the pad, may be in the position shown in Fig. 1, or in the position shown in Fig. 2, the sheets generally being transferred day by day from the right to the left hand side.

To hold these sheets in position, the base is 50 provided with a pair of posts 14 and 15, each of which has a pair of legs 16 and 17 respectively on opposite sides of the median line of the base and which may be threaded through suitably spaced openings in the calendar pad. A semi-circular loop joins the legs 16 and 17 as at 18 and the

leaves of the pad are threaded through this loop from the right to the left leg, or vice versa.

The posts 14 and 15 may be mounted in any suitable way being, generally or preferably, mounted so as to lock in the upright position shown in Figs. 1 and 2 when in working position, or to be tilted toward a horizontal position for filling. For this purpose the posts 14 and 15 extend downwardly below the base 10, as shown in Figs. 4 and 5, and are joined by a cross or connecting piece 19 which fits into a recess 20 of each one of a pair of depending brackets 21 near the respective posts 14 and 15 in such a manner as to tilt from the upright position of Figs. 1 and 2 to an inclined position, which would bring the right leg 17 above the base so that the calendar pad may be removed or threaded onto the leg.

To permit the posts to tilt, slots 22 are formed in the base. To hold the posts in the recess 20, and to normally assume the upright position, the connecting rod 19 is bent as at 23 and connected to a slide 24 which in turn carries a spring 25 confined between and compressed between the part 23 and the down-depending bracket 26 so as to press the post to upright position. The leg 17 of each post is notched near its lower end as at 27 to engage the base and lock the posts in position.

In applying my present invention to a calendar of the above type, an instrument support, such as that shown at 28, is provided with a plate 29 to rest on the upper part of the base 10. The plate 29 is less than the width of the base 10 but somewhat greater than one-half the width of the base and is provided with a pair of slots 30 and 31 through which the posts 14 and 15 may project when the plate 29 is placed on the base 10. The slots 30 and 31 are ample to permit the posts 14 and 15 to be tilted downwardly to filling position with the plate 29 on the base so that a calendar pad may be threaded onto the open legs of the posts after the plate 29 has been placed on the base. When the pad has been placed in position and the posts tilted to their upright position, the weight of the pad holds the plate 29 firmly onto the base. When the pad is mainly on the right of the base as, for example, at the start of the year, it is desirable to have the instrument support 28 at the left hand side of the pad to give better vision, but as the calendar pad is transferred to the left in the latter part of the year, the instrument support should be shifted to the right. Slots 30 and 31 are of sufficient length to permit this to be accomplished as shown in Figs. 1 and 2.

The instrument support may be of any suitable construction or type or design. In the embodiment shown in the drawings it consists of an upwardly inclined extension 32 of the plate 29 having an opening which may accommodate an instrument, such as the thermometer and humidity gauge or hygrometer 33, the dial of which is clearly visible from the front of the plate. It will be understood that other types of instruments or dials or articles may be substituted for the thermometer and humidity gauge illustrated by way of example in the accompanying drawings.

The instrument support may be supplied as a separate article of commerce, being readily insertable on calendar pads already in use by the purchaser, or supplied to dealers to be sold with the calendar pads upon demand as an assembled unit.

The instrument support may be applied to other types of calendar pads as, for example, of the type shown in Figs. 6, 7 and 8. In this type of calendar a base 34 is provided with a pair of threaded studs 35 and 36 which are inserted through openings, such as those shown at 37 in the calendar pad 38, Fig. 8. The calendar pad thus mounted on the base is held in place by a clamping plate 39 covering a narrow margin at the upper edge of the calendar pad and having openings through which the upper ends of the posts 35 and 36 project and on which is threaded a nut 40.

In applying the instrument support to a calendar of the above type, the plate 29 is placed on the base 34 near the upper edge of the base after which the calendar pad is placed in position and the clamping plate and assembly secured by the nuts 40. The instrument support is thus firmly clamped into the base until the calendar pad is replaced.

To enable the instrument support to be mounted on bases of the above type, openings or notches 41 and 42 may be provided to receive the posts 35 and 36. However, where the posts are so spaced as to fit into either of the slots 30 or 31, this may be done.

Through the above invention I provide a support for articles, such as thermometers, timer-pieces, hygrometers, etc., that may be readily mounted on a variety of desk calendars and which enables the dial or indicator of the instrument to be readily visible without giving it undue height.

What I claim is:

1. A desk calendar having a base to support calendar pad sheets on either the right or left half of said base, a pair of spaced upright sheet-holding posts each having a pair of legs extending upwardly from said base and in a plane parallel to the upper edge of said base so that a calendar sheet can be turned from the right half of said base to the left half, and vice versa, while threaded on said legs, an instrument support comprising a plate of less width than that of said base and slidably resting on said base and having a pair of slots spaced to receive said posts and of such a length that said plate can slide to a position to extend over either the right or the left of said base and an instrument-carrying upright connected to said plate.

2. A desk calendar having a base to support calendar pad sheets on either the right or left half of said base, a pair of spaced upright sheet-holding posts each having a pair of legs extending upwardly from said base and in a plane parallel to the upper edge of said base so that a calendar sheet can be turned from the right half of said base to the left half, and vice versa, while threaded on said legs, an instrument support comprising a plate of less width than that of said base and slidably resting on said base and having a pair of slots spaced to receive said posts and of such a length that said plate can slide to a position to extend over either the right or the left of said base and an instrument-carrying upright connected to said plate, said upright comprising an upward extension of said plate and having an opening therein and an instrument mounted in said opening.

JOHN F. BANNON.
